DESIGN FOR A TELEPHONE JACK

Carl Lomholt, Bogota, N. J., assignor to Federal Telephone and Radio Corporation, New York,
N. Y., a corporation of Delaware

Application March 30, 1945, Serial No. 118,795

Term of patent 14 years

(Cl. D26—13)

To all whom it may concern:

Be it known that I, Carl Lomholt, a citizen of the United States, residing at 189 Central Avenue, Bogota, Bergen County, State of New Jersey, have invented a new, original, and ornamental Design for a Telephone Jack, of which the following is a specification, reference being had to the accompanying drawing, forming part thereof.

Fig. 2 is a front elevational view of the telephone jack shown in Fig. 1, the dotted line showing of Fig. 1 having been omitted; and

Fig. 3 is a rear elevational view of the telephone jack shown in Fig. 1, the dotted line showing of Fig. 1 having been omitted.

The characteristic features of my design are shown by means of full lines in the drawing.

I claim:

The ornamental design for a telephone jack, as shown and described.

CARL LOMHOLT.
